(57) **CLAIM**

The ornamental design for an inflatable floating bed, as shown and described.

DESCRIPTION

FIG. 1 is a first perspective view of an inflatable floating bed showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1;

FIG. 10 is an enlarged view of the selected portion in FIG. 1; and,

FIG. 11 is an enlarged view of the selected portion in FIG. 1.
